SHOULDER HARNESS WALLET HOLDER

Lawrence C. Shoberg, 1427 San Thomas Road,
San Jose, Calif. 95130

Filed Dec. 9, 1974, Ser. No. 530,514

Term of patent 14 years

Int. Cl. D2—07

U.S. Cl. D2—400

FIG. 1 is a perspective view of a shoulder harness while in the holder showing my new design in the "in use" position;

FIG. 2 is a right side elevational view of the lower holder portion of the harness, the upper portion having been omitted for convenience of illustration;

FIG. 3 is a front elevational view of FIG. 2 including the harness rings, the remainder of the harness having been omitted for convenience of illustration.

The rear and other portions of the harness not shown, are substantially flat, plain and unornamented, and generally conform to the sides shown.

I claim:

The ornamental design for a shoulder harness wallet holder, substantially as shown and described.
